UNITED STATES PATENT OFFICE.

ALFRED HERZ, OF CHICAGO, ILLINOIS, ASSIGNOR OF ONE-HALF TO EDMUND O. SCHWEITZER, OF CHICAGO, ILLINOIS.

LIGHT-DIMMING MECHANISM.

1,195,123.

Specification of Letters Patent. Patented Aug. 15, 1916.

Application filed March 18, 1915. Serial No. 15,273.

To all whom it may concern:

Be it known that I, ALFRED HERZ, a citizen of the United States, residing at Chicago, in the county of Cook and State of Illinois, have invented a certain new and useful Improvement in Light-Dimming Mechanism, of which the following is a full, clear, concise, and exact description, reference being had to the accompanying drawings, forming 10 a part of this specification.

The present invention relates to light dimming mechanism and is particularly applicable to alternating current distributing systems. There is a very considerable demand 15 by the public for an inexpensive means for "turning down" or dimming a standard electric light such as the modern 25 or 40 watt tungsten lamp so that the same may be used for a night lamp, giving out only sufficient 20 light to illuminate the outlines of objects in a room or the like.

Numerous attempts have been made in the prior art to provide mechanisms which will allow greater or less voltage to be applied individually to a standard lamp so as to cause greater or less current to flow through the filament and thereby increase or decrease the amount of light given out. One type of these devices switches the lamp current through a resistance to diminish the voltage impressed upon the lamp. Devices of this type have not met the demand because of the waste of energy which their use entails. The resistance dissipates the 30 energy in the form of heat instead of using it in the lamp and as a result no saving of any consequence is effected. In devices of this kind, it has also been customary to connect the lamp terminals either to the resistance or directly to the line. This requires the entire current to be switched and requires a switch of rather substantial structure to accomplish the same. Another type with which I am familiar employs two independent filaments in the body of the lamp. The current is switched from the low resistance high wattage filament to the high resistance low wattage filament to diminish the illumination. This type of device is objectionable 40 being of high first cost and requiring a special lamp. If either filament is broken the lamp is useless for the present purpose.

It is the object of the present invention to provide a simple and economical light dim-

ming mechanism which will meet the above 55 demand. I accomplish this by employing an inductance coil in series with the lamp filament for the low illuminating condition and by short circuiting the inductance coil for the normal or high illuminating condition. 60 This allows of the employment of a small and easily operated switch inasmuch as very little current passes through the same.

A further object is to provide an improved inductance coil for use in the above 65 or any similar situation.

In the accompanying drawings which form a part of the present specification, I have illustrated one embodiment in which my invention may appear. 70

Figure 1 is a vertical longitudinal section of a light dimming mechanism embodying my invention. Fig. 2 is a detail view taken at right angles to Fig. 1, with a portion of the outer casing or shell broken away. Fig. 75 3 is a plan view of the same with the shell and lower sockets removed. Fig. 4 is an end view of the inner core of the inductance coil. Fig. 5 is a wiring diagram of the dimmer shown in Fig. 1. Fig. 6 is a modification of the stem and handle of the switch, and Fig. 7 is an elevation of the lamp dimmer in place and installed ready for use, the reflector or shade of the lamp being broken away to reveal the relation of the parts. 85 Fig. 8 is a central cross sectional view of the above device. Fig. 9 illustrates one of the radially slotted disks.

The lamp dimmer as shown in Fig. 1 consists essentially of an upper plug 1, a lower 90 socket 2, an inductance coil 3 connecting the plug and the socket and a switch 4 for short circuiting the inductance coil. The inductance coil comprises a central hollow core 5 of magnetic material, heads 6 and 7 also of 95 magnetic material, an outer cylindrical shell 8 of magnetic material and a winding 9 wound upon the inner core 5 and surrounded by the cylindrical shell 8. The central hollow core 5 is built up from a sheet of 100 silicon steel by rolling the same in a spiral roll, as indicated in Fig. 4. The core is then insulated by the wrapping 10 of paper, transformer linen or the like. The heads 6 and 7 of the inductance coil are built up 105 from a plurality of circular disks of silicon steel having an aperture through the central portion thereof for receiving the insulating

sleeve 11 which passes through the heads and through the core 5. The core 5 and the heads 6 and 7 are not in contact with each other, but are separated by insulating washers 12. A block of insulation 13 which forms the body of the plug 1 is seated on top of the inductance coil and the block of insulation 14 which forms a base for the socket 2 is seated on the bottom of the inductance coil. A bolt 15 threaded at both ends passes through both of these blocks and through the sleeve 11, and holds the parts together by means of the slotted head 16 and the slotted nut 17 which form the central terminals of the plug and the socket 2 respectively. A flat nut 18 may be threaded on the rod 15 for holding the block of insulation 14 to the inductance coil while the parts are being assembled. The plug 1 is provided with a cylindrical metal shell which is externally screw threaded to cooperate with the standard lamp socket, such as is shown in Fig. 7. This shell 19 forms one terminal of the plug 1. The bottom of the shell 19 is turned inwardly to form a flange and the flange is gripped between a shoulder formed on the block of insulation 13 and the ring of insulation 20 which surround the reduced portion of the block 13, as shown in Fig. 1. The block of insulation 14 at the bottom of the inductance coil 3 supports in addition to the threaded socket 2 the members of the switch 4. This switch comprises essentially a moving spring contact portion 21 (see Fig. 3) and an anvil portion 22 which is stiffened by flange 23 bent at right angles thereto. A bracket 24 secured to the block 14 and having the parallel flanges 26, supports a switch shaft 27 upon which is mounted a block of insulation having square faces for coacting with the spring member 21 and for securing a snap action when the switch is opened and closed. One end of the coil 3 is connected by means of a wire 29 with the socket shell 2 which is mounted on the block of insulation 14 and held there by means of the screws 30. The other end of the inductance coil 3 is connected to the shell 19 of the plug 1 by means of the screws 31. A wire 32 which is also connected by the screws 31 to the shell 19 of the plug 1 is held in contact with the terminal of the movable switch member 21 and serves as the connection for short circuiting the inductance coil 3 when the light is to give normal illumination.

The coil 3, the switch 4 and the socket 2 are protected by a casing 33 which is divided into two parts for ready assembly, the parts being held together by the small screws 34. The upper half of the casing is provided with a bracket 35 which is secured by means of a screw 36 to the ring of insulation 20 which is pinned to the shell 19 and the block of insulation 13 forming a

part of the plug 1. The lower half of the shell is secured by means of a similar bracket 37 and screw 38 to the lower block of insulation 14 which is secured to the socket 2. The shell 33 serves as means to prevent relative rotation of the parts and prevent damage to the connections. A sleeve of insulation 39 prevents contact between the socket 2 and the shell 33. A switch stem 27 extends through an opening 40 in the casing 33 and lies adjacent the bulb 41 of the lamp which is screwed into the socket 2. The lower portion of the stem 27 is made flexible as by forming the same of a coiled spring 42 connected by means of the couplings 43 and 44 to the stem 27 and the insulate key 45 respectively. This stem is made flexible in order to prevent any undue strain being placed upon the switch mechanism and in order to prevent injury or deformation of the same. The lower portion of the casing 33 is provided with a pair of flanges 46 between which may be secured the strap 47 of a shade bracket 48. The flexible portion 42 of the stem 27 lies between the lamp bulb 41 and the shade 49 in order that the same may readily be distinguished in the dim light given out by the lamp when the same is turned down. The plug 1 is screwed into the usual socket 50 provided with the key 95 switch 51 for turning current off and on to the terminals of the socket.

In Fig. 6, I have illustrated another manner in which this switch stem 27 may be built up. In this case the switch stem 27' comprises a piece of steel wire which is secured to a key 45' and upon which are threaded ornamental beads 52 of any preferred design. When it is desired to turn down the lamp, the button 45 is turned to the position in which the coil 3 is included in circuit as shown in Fig. 5 or as shown in Figs. 1, 2 and 3. When the lamp is to be brought to full illuminating power the key is given a quarter turn so that the spring 21 110 is pressed against its anvil 22 and the inductance coil 3 is short circuited.

The inductance coil, which I have described above I consider to be of novel design. All of the parts are made up of laminations of silicon steel in which the specific resistance is very high for preventing loss by eddy currents. The laminations of the core 5 prevent any considerable losses therein and the disks comprising the heads 6 and 7 120 are slotted radially to prevent eddy currents circulating therein. The outer shell casing is formed in a manner similar to the core 5, that is, by wrapping a sheet of silicon steel about the heads 6 and 7 to close the magnetic circuit. It will be noted that the magnetic circuit is open between the core 5 and the heads 6 and 7, the insulation 12 being interposed therebetween. This gap may be made of any desired amount which gives the 130

proper inductance. I consider this core to be broadly new and intend to claim the same as such.

It can readily be appreciated that the above dimmer can be constructed at a low expense and that it will effect a very marked saving over any of the devices now in the market. The efficiency of the inductance coil, above set out, as compared with a transformer is very marked. The transformer is constantly in circuit and has a constant energy loss which is not true of the inductance coil inasmuch as the same is short circuited during the period when the lamp is at normal illumination. As compared with a resistance cut into or out of circuit the present method of employing an inductance coil is far superior. The only loss which occurs in the present structure is that due to magnetization of the iron and as will be readily comprehended by those skilled in the art this is a very small amount, due to the fact that it occurs only during the time when the lamp is turned down. The mechanism is particularly noiseless and embodies to a marked degree, ease of control. The switch handle is always in sight and requires but a very slight effort to operate the switch inasmuch as only a small quantity of current needs to be switched. The inductance coil reduces the voltage impressed upon the lamp from 110 or 120 to about 30 or 40 volts.

I employ the term spool in the specification and claims to designate the core which serves as a spool to receive the winding. I do not mean thereby to confine myself to employing a strictly spool shaped core, or that the spool heads, to which I refer in the claims, must necessarily be separate and distinct parts of the core, as the core may be made substantially cylindrical and the part mounted upon the ends, which correspond to similar parts of a spool.

While I have described the one particular embodiment of my invention with considerable detail, I do not intend thereby to limit my invention to any particular detail described or illustrated, as I consider that the invention is capable of being embodied in a variety of forms and with numerous modifications all as will be apparent to those skilled in the art.

What I claim as new and desire to secure by Letters Patent is the following:

1. In a device of the class described, an inductance coil comprising a magnetic core, a plug and a socket mounted on said core, a winding inclosing said core, said winding connecting said plug and said socket, and a switch for switching said winding into and out of circuit with said socket.

2. In combination, a magnetic spool, a plug and a socket mounted on the ends of said spool, an inductive winding mounted on said spool, said winding connecting said

plug and said socket, a switch for switching said winding into and out of circuit with said socket, and a shell inclosing said spool, said inductance coil and said socket.

3. In combination, a magnetic spool, a plug and a socket mounted on the ends of said spool, an inductive winding on said spool, said winding connecting said plug and socket, and a switch for short circuiting said inductive winding. 75

4. In combination a magnetic spool, a plug and a socket mounted on the heads of said spool, said plug and said socket having each a threaded shell, a bolt forming a common contact for said plug and said socket and passing through said spool, a winding mounted on said spool and connecting the threaded shells, and a switch for switching the winding into and out of circuit. 85

5. In combination a magnetic spool, a plug and a socket mounted on the head of said spool, said plug and socket having threaded shells, a bolt forming a common contact for said plug and for said socket, 90 said bolt passing through said spool, a winding connecting the threaded shells, said winding being disposed on said spool, a switch for switching the winding into and out of circuit, and a casing inclosing said spool and 95 said socket.

6. In combination a spool of magnetic material, a plug and a socket mounted on the heads of said spool, said plug and said socket having each a threaded shell, a bolt 100 forming a common contact for said plug and said socket and passing through said spool, a winding on said spool connecting the threaded shells, a switch for switching said winding into and out of circuit, and a 105 casing inclosing said winding, said switch and said socket.

7. In combination a spool of magnetic material, a plug and a socket mounted on the ends of said spool, a coil between said 110 plug and said socket, a bolt connecting said plug and said socket and passing through said spool, a casing surrounding said coil, said casing having lugs for preventing relative rotation of said plug and said socket. 115

8. In combination a spool of magnetic material, a plug and a socket mounted on the heads of said spool, a shell inclosing the spool and the socket, and fastening means for the plug, spool and socket serving 120 as a central common contact for plug and socket.

9. In combination, a cylindrical magnetic core, a block of insulation secured to each end thereof, plug contacts mounted on one 125 of said blocks, socket contacts mounted on the other block, a winding on said cylindrical core and circuit connections between said plug contacts and socket contacts, said circuit connections including said winding. 130

10. In combination a spool shaped magnetic core, a block of insulation secured to each end of said core, plug contacts mounted on one of said blocks, socket contacts mounted on the other, a winding on said core, circuit connections between said plug and socket including said coil and a switch mounted on one of said blocks, said switch operating to cut said coil into and out of 5 circuit.
11. In combination a spool shaped magnetic core, a block of insulation mounted on each end of said core, plug contacts mounted on one of said blocks, socket contacts mounted on the other block, and a bolt for holding said blocks of insulation to said core, said bolt passing through said blocks and through said core and forming an electrical connection between said plug and said 15 socket.
12. In combination a magnetic spool, a block of insulation secured to each head thereof, a winding on said spool, plug contacts mounted on one of said blocks, socket contacts mounted on the other block, circuit connections between said plug and socket contacts, including said winding and a bolt for holding said blocks of insulation to said 20 core.
13. In combination a magnetic spool, a block of insulation mounted on each head of said spool, plug contacts mounted on one of said blocks, socket contacts mounted on the other block, a winding on said spool, circuit 25 connections between said plug and said socket contacts, said connections including said winding, a bolt for holding said blocks of insulation to said core, said bolt serving as a common contact for said plug and for 30 said socket, and a switch mounted on the block of insulation supporting the socket.
14. In combination a magnetic spool shaped core, a block of insulation secured to each head of said core, plug contacts mounted on one of said blocks, socket contacts 35 mounted on the other of said blocks, a winding on said core, a bolt for holding said blocks of insulation to said core, and circuit connections including said bolt and said coil and a rotary switch mounted on 40 one of said blocks and having an operating shaft substantially parallel with the axis of said core, said switch operating to cut said coil into and out of said circuit.
15. In combination, a magnetic spool, a block of insulation secured to each spool head, a socket mounted on one block, a plug mounted on the other, a coil mounted on said spool, said coil having its ends connected to a terminal of said socket and a 45 terminal of said plug, a snap-switch and a connection for short-circuiting said coil.
16. In combination, a magnetic spool, a block of insulation mounted on one head of said spool, a connecting plug mounted on 50 said block, another block of insulation mounted on the other head of said spool, a connecting socket mounted thereupon, a rotary snap-switch mounted on said latter block, a winding on said spool, said winding connecting said plug and socket, said switch being connected across the terminals of said winding.
17. In combination, a magnetic spool, a block of insulation mounted on the head of 55 said spool, a connecting plug mounted on said block, another block of insulation mounted on the other head of said spool, a connecting socket mounted thereupon, a pair of switch contacts mounted on said latter 60 block, a rotary switch operating shaft, extending substantially parallel with the axis of said spool, and a handle on said shaft for operating said switch contacts.
- In witness whereof, I hereunto subscribe 65 my name this 16th day of March, A. D. 1916.
- ALFRED HERZ.
